UNITED STATES PATENT OFFICE.

WILLIAM W. CAMERON, OF LA CROSSE, WISCONSIN, ASSIGNOR TO LA CROSSE PLOW COMPANY, OF LA CROSSE, WISCONSIN, A CORPORATION OF WISCONSIN.

GRAIN-DRILL.

1,118,918.

Specification of Letters Patent.

Patented Dec. 1, 1914.

Application filed December 19, 1910. Serial No. 598,245.

To all whom it may concern:

Be it known that I, WILLIAM W. CAMERON, a resident of La Crosse, in the county of La Crosse and State of Wisconsin, have 5 invented certain new and useful Improvements in Grain-Drills, of which the following is a full, clear, and exact description.

The invention relates to grain-drills, and more particularly to that type in which 10 seeding-mechanism and furrow-openers are sustained by a front carrying wheel, rear caster wheels, and a jointed supporting structure between said wheels, which permits the furrow-openers to be raised and 15 lowered. In this type of grain-drill it has been the practice to raise and lower the furrow-openers and seeding mechanism by means of a handle rigidly secured to the machine in such manner that bodily lift of the 20 front member of the supporting structure was necessary to raise the seed-box and furrow-openers. In such mechanism, considerable exertion upon the part of the operator, was necessary in effecting or controlling the 25 raising and lowering operations, because the handle was rigidly secured to the structure, and failed to afford efficient leverage to aid the operator and facilitate these operations.

The present invention designs primarily 30 to provide in this type of drill, lever-operated raising and lowering mechanism for the furrow-openers and seed-box, comprising a lever which is fulcrumed on the structure, so that an effective leverage will be attained to facilitate the raising and lowering 35 operations.

The invention further designs to provide 40 a grain-drill embodying improved features of construction. The invention consists in the several novel features hereinafter set forth, and more particularly pointed out by claims at the conclusion hereof.

In the drawings: Figure 1, is a side elevation of a grain-drill, embodying the invention, the furrow-openers being shown in lowered position. Fig. 2, is a similar view, showing the furrow-openers in raised position. Fig. 2^a, is a section taken on line 2^a—2^a, of Fig. 3. Fig. 3 is a plan, parts being removed.

The improved grain-drill comprises a front carrying-wheel *a* mounted on a shaft *a'*. Said shaft is held in bearing brackets *a²*, which are secured to the front frame supporting member *b*, which comprises side-

bars *b'* having their front ends secured to a clevis-bar *c* by a bolt *c'* and their rear terminals extended upwardly as at *c²* to support the seed-box *6*. This front-frame is tiltably sustained by shaft *a'* and the carrying wheel *a*, to swing about the wheel-axis and to permit the rear portion of the frame to be raised or lowered, to correspondingly shift the furrow-openers and other mechanism sustained by the frame and seed-box. 60

A rear frame *d*, comprising a cross-bar *d'* and side bars *d²*, is pivotally connected to the tilttable front-frame, by pivot-bolts *d³*, which pass through the front ends of the side-bars of the rear-frame and through the 70 side-bars of the front-frame respectively. The rear portion of the rear-frame *d* is sustained by caster-wheels *e*, each of which is journaled on a suitable arm *e'*, which has its front end pivotally held in a bracket *d⁴*, 75 secured to the rear-frame *d*.

The front and rear frames, carried by the front wheel *a*, and caster-wheels *e*, respectively, and the pivoted connection between them, constitute a jointed supporting structure whereby the mechanism supported by the front-frame, may be raised and lowered to correspondingly shift the furrow-openers and seed-box carried thereby. The tilting 80 of this front-frame is controlled by lever-mechanism, hereinafter set forth.

The grain-drill shown is of the type commonly known as a "one-horse" drill, in which there is provided a central furrow-opener *f*, an intermediate opener *f'* at each 90 side thereof, and an outside furrow-opener *f²* at each side of the frame *b*. Each of these furrow-openers consists of a suitable disk 10, usually set at an angle to line of draft to cut a furrow as it is drawn through the 95 soil. Each furrower-opener is provided with a seed-boot 23, which is suitably secured to its associated drag-bar, as is well understood in the art. Furrow-openers *f*, *f'* are each suitably mounted on a drag-bar *f³* as 100 well understood in the art. The front ends of these drag-bars are connected to a cross-rod or shaft 12 which extends between, and is secured in the side-bars *b'* of the front frame *b*. Each of the drag-bars *f³*, for openers *f'*, has its front end secured to a lug on a coupling or sleeve 13, which is slidably and pivotally mounted on cross-rod 12, so that by lateral or sliding adjustment thereof, the spacing between the center furrow. 110

opener f and the openers f' may be varied to cause them to cut furrows different distances apart. The drag-bar f^3 for the central furrow-opener f , has its front end secured to a rearwardly extending lug 14^a on a coupling 14 which is secured against lateral movement on the cross-rod 12, by a pin 15^a which extends through a vertical slot 15^c, in the coupling, to permit this drag-bar to swing responsively to its pressure device.

The lateral adjustment of furrow-openers f' is controlled by a hand-lever 16 which is provided at its rear with a handle 17 which is accessibly disposed to the operator walking at the rear of the machine, and is pivotally connected, as at 16', to an arm on the bell-crank lever 18 which is pivoted on coupling 14, being pivotally held on a bolt 15, which is secured in coupling 14.

20 Lever 18 comprises two oppositely extending arms 19 to each of which a link 20 is pivoted, and the outer ends of these links are pivoted as at 21 to the sleeves 13, respectively. Resultantly, lever 18, when 25 shifted about its pivot 15, will shift coupling sleeves 13 on the cross-rod 12, inwardly or outwardly, to correspondingly adjust drag-bars f^3 and the furrow-openers f' carried thereby. The rear portion of lever 18 is 30 held in a guide-lug 22 which is secured to the seed-boot 23 for the central furrow-opener f , and has notches 23' in its lower edge for engaging the guide-lug to lock the lever in its different positions.

35 Each of the drag-bars f^3 is yieldingly sustained adjacent its rear by a pressure device, comprising a rod 24 pivoted at its lower end to the drag-bar, and having its upper end slidably held in a lug 25 which is secured to the seed-box and a spring 26 applied to resist the upward movement of the drag-bar. A stop pin 27 at the upper end of rod 24 limits the downward movement of 40 the drag-bar relatively to the seed-box. By 45 means of these connections these drag-bars and furrow openers will be raised and lowered with the seed-box, and the rear portion of the front supporting frame to which said box is secured.

50 Each of the furrow-openers f^2 is sustained by a drag-bar f^5 which is disposed outside of the supporting frame-work, and is connected at its front end to a forked coupling 30, which is connected to swing laterally, to projecting lugs on one of the brackets a^2 . Brace-rods 31 extend through brackets a^2 and couplings 30 to pivotally connect them, and are extended rearwardly to the seed-box, where-to the rear terminal of said rods are secured. 55 Each of the seed-boots for the outside furrow-openers is connected to the seed-box by a strap 32, which has its ends pivoted to the seed-boot and seed-box, respectively. Each drag-bar f^5 is controlled laterally by a 60 spring-connection comprising a rod 33 hav- 65

ing its outer end pivoted in a lug 34 on the drag-bar, and having its inner end slidably and pivotally connected to the sleeve 13, and a coil-spring 35. These connections for the outer furrow-openers f^2 cause them to be yieldingly and automatically shifted with the furrow-openers f' .

70 The seed-box is provided with a seed-delivery mechanism 37 of usual construction, whereby the seed will be discharged in regulated quantity, into flexible seed-tubes 36 which conduct the seed into the seed-boots, which deliver the seed into furrows. Seed-delivery mechanism 37 is driven by a chain 38, and sprocket 39, which is operatively connected to the front-wheel a by a suitable clutch 40 and a lever 41, of usual or any suitable construction controls the operation of the clutch and the driving mechanism for the seed-delivery mechanism.

75 In grain-drills of this type, as heretofore constructed, the handles for raising and lowering the seed-box and furrow-openers, were rigidly connected to the seed-box and resultantly it was necessary for the operator to 80 lift the seed-box and parts vertically movable therewith, bodily about the fulcrum of the front-frame or wheel-axis, and in thus adjusting the furrow-openers from lowered to raised positions and vice versa, considerable power and inconvenience was necessary, because sufficient leverage to facilitate shift was lacking. In the present invention, a 85 lever-mechanism is provided by which the raising and lowering operations are greatly 90 facilitated and rendered easy. This lever-mechanism comprises a lever 42 for operating, and disposed at, each side of the machine. Each lever 42 is pivoted as at 43 to an arm 44 integrally formed with a seg- 95 mental rack 45 which is rigidly secured to the seed-box at 46, and to the side-bars of the front-frame b as at 47. Each lever 42 is 100 fulcrumed upon a link 48 by a pivot-bolt 49, and each link has its lower end pivoted as 105 at 50, to the rear-frame d of the jointed supporting structure. Each lever 42 is 110 provided with a lock 51 controlled by a finger-lever 52, and adapted to engage with its rack 45 to lock the lever-mechanism in its 115 different positions. Each link is provided with a hole 48^a which permits, by disconnection of bolts 50 and insertion through said holes, the levers 42 to be adjusted for the convenient reach of different operators. 120 Levers 42 are cross-connected for conjoint operation, by a bar 53. Guards 54 are secured to the lever-handles 55 to protect the 125 hands of the operator from being struck by stalks.

130 In operation, when the furrow-openers are lowered into the soil, the openers, seed-box and associated devices, may be easily raised by depressing the handles 55 of levers 42, the locks 51 being first released

from racks 45. When downward pressure is applied to these handles, levers 42 will be operated about their fulcra 49 which will cause their front ends which are pivoted 5 to racks 45, which are rigid with the front-frame *b* to easily raise the front-frame and all the devices sustained thereby, including the seed-box and furrow-openers, the said frame moving pivotally about the axis of 10 wheel *a*. In this operation the rear frame *d*, which is sustained at its rear by caster-wheels *e*, will furnish a support for the fulcrum-links 48 and the latter will permit the rear-frame *d* to swing about its pivotal 15 *d*³ connection and to move relatively to the front frame. Obviously, in this operation, these levers, being fulcrumed at 49, raise the mechanism by means of their comparatively short arms, which are disposed for 20 wardly of the fulcra, and therefore efficient and powerful leverage is attained whereby the operator can easily and readily raise the furrow-openers and seed-box, and can readily control the lowering operation. Furthermore, levers 42 serve as handles for 25 guiding the machine, and the operator can manipulate the locks for the lever-mechanism, by finger-levers 52 without releasing the handles. Upon release of the finger-levers the locks will become operative to 30 lock the lever-mechanism and supporting structure in assigned position. The depth of the furrows cut by the openers may be readily varied by adjusting the levers 42 and locking them in different positions, 35 racks 45 being provided with notches for locking the levers in such positions.

The distance between the furrows may 40 be varied by means of lever 16, which, when shifted, will rock lever 18 about its pivot 15 which is fixed against lateral movement on rod 12, and said lever 18 will shift links 20 in opposite directions and correspondingly shift couplings 13 and the furrow-openers 45 *f*¹ carried thereby, said couplings sliding on cross-rod 12. Sleeves 13, will, by means of yielding connections 33, 35, correspondingly shift the furrow-openers *f*². This mechanism thus provides simple means for 50 adjusting the spacing between the furrow-openers.

The invention is not understood as restricted to the details set forth, since these 55 may be modified within the scope of the appended claims, without departing from the spirit and scope of invention.

What I claim as new and desire to secure by Letters Patent, is:

1. The combination of front and rear 60 wheels, a jointed supporting structure sustained by said wheels, the furrow-openers mounted to be raised or lowered by said structure, seed-delivery mechanism, a lever pivotally mounted on the structure and for 65 adjusting the structure to shift the furrow-

openers, the lever being extended rearwardly of the rear wheels, and provided with a handle whereby the machine may be guided by lateral shift of the lever, and locking means for the lever. 70

2. The combination of front and rear wheels, a supporting structure comprising two members respectively connected to the front and rear wheels and a pivotal connection between said members, furrow-openers 75 sustained by said structure and mounted to be raised or lowered by adjustment of said members, seed-delivery mechanism sustained by said structure, a lever for operating said structure to raise or lower the openers, a fulcrum about which the lever will swing, sustained by one member of the jointed structure, and an operating connection between the lever and the other member, said lever extending rearwardly of the rear 80 wheels and being provided with a handle whereby the machine may be guided by lateral shift of the lever. 85

3. The combination of front and rear wheels, a supporting structure comprising 90 two members mounted to swing about the axes of the front and rear wheels respectively, and a pivotal connection between said members, furrow-openers mounted to be raised or lowered by said structure, a lever 95 pivotally connected to one member of said structure, and a fulcrum for said lever mounted on the other member, said member being extended rearwardly of the rear wheels and provided with a handle whereby 100 the machine may be guided by lateral shift of the lever.

4. The combination of front and rear wheels, a supporting structure comprising 105 two members mounted to swing about the axes of the front and rear wheels, respectively, and a pivotal connection between said members, furrow-openers mounted to be raised or lowered by said structure, seed-delivery mechanism, a lever, a lever-fulcrum 110 sustained by one of said frames, and an operating connection between the lever and front frame, extending rearwardly of the rear wheels and being provided with a handle whereby the machine may be guided by 115 lateral shift of the lever.

5. The combination of front and rear wheels, a jointed supporting structure sustained by said wheels, comprising members pivotally connected together, furrow openers mounted to move with one of said members, seed-delivery mechanism, a lever pivotally connected to one member of said structure, a connection between said lever and the other member of the structure, said member being extended rearwardly and provided with a handle for guiding the machine, and means for locking the lever in different positions to secure the members of said structure in different relative positions. 130

6. The combination of a frame, a cross-rod sustained by said frame, a central furrow-opener, adjustable furrow-openers disposed laterally of the central opener, couplings 20
5 slidably mounted on said cross-rod, and to which the adjustable furrow-openers are secured, mechanism for laterally adjusting said couplings, comprising a lever having 25
10 oppositely extending arms, links between said arms and said couplings, respectively, and a hand-lever pivoted to the lever having arms, a coupling for the central opener, pivoted on said rod, a pin-and-slot connection 30
15 between said latter coupling and said rod, and a pivot-bolt between the armed lever and said latter coupling.

7. The combination of a frame carrying-wheels, a cross-rod sustained by said frame, a central furrow-opener, adjustable

furrow-openers disposed laterally of the central opener, mechanism for raising or lowering said openers, couplings slidably mounted on said cross-rod, and to which the adjustable furrow-openers are secured, mechanism 20
25 for laterally adjusting said couplings, comprising a lever having oppositely extending arms, links between said arms and said couplings, respectively, and a hand-lever pivoted to the lever having arms, a coupling 30
30 for the central opener, pivoted on said rod, a pin-and-slot connection between said latter coupling and said rod, and a pivot-bolt between the armed-lever and said latter coupling.
